CLAIM

The ornamental design for an electric motorcycle, as shown and described.

DESCRIPTION

FIG. 1 is a top, front and right side perspective view of an electric motorcycle showing my new design;

FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged detail view of area 9 in FIG. 1;

FIG. 10 is an enlarged detail view of area 10 in FIG. 1; and, FIG. 11 is an enlarged detail view of area 11 in FIG. 1.

The dash-dot-dash broken lines in FIGS. 1 and 9-11 indicate the boundaries of the enlarged views and are used annotative purpose only. They do not limit or define the scope of the claimed design.

1 Claim, 11 Drawing Sheets
